UNITED STATES PATENT OFFICE

ERNEST C. LEACH, OF WEST PEABODY, MASSACHUSETTS, ASSIGNOR TO LYNN PRODUCTS CO., OF LYNN, MASSACHUSETTS, A CORPORATION OF MASSACHUSETTS

OIL BURNER AND SUPPORT THEREFOR

Application filed July 22, 1930. Serial No. 469,661.

This invention relates to range oil burners and more particularly to devices for locating the combustion chambers, usually of a twin burner, within the fire pot and below the 5 lids of the range.

Range oil burners of the type disclosed in the United States patent to Johnson and Leach No. 1,764,794 dated June 17, 1930, owned by the assignee of this invention, are 10 sold generally to householders and because of the large variety of types of domestic ranges still in use it is essential that there be sufficient flexibility or universality in the burner mountings to enable a proper installation regardless of any special feature of 15 construction within the fire box.

With this object in view the present invention comprises the features and combinations of parts hereinafter described and then particularly pointed out in the appended claims; and its nature and scope will be understood 20 from a description of the preferred embodiment illustrated in the accompanying drawings, in which:

Figure 1 is a view, in perspective, of the 25 complete burner support;

Fig. 2 is a perspective view of the adjuster, detached; and

Figs. 3 and 4 are views, in section, of the 30 fire boxes of two different types of range illustrating the use of the adjuster in effecting a proper installation of the burner.

In the embodiment of the invention illustrated in the drawings the oil burner may be 35 of any of the well known types now on the market and the illustration in Figs. 3 and 4 represents the twin burner of the above named Johnson and Leach patent having a web 2, joining the two combustion chambers 4, 40 drilled or otherwise perforated to receive a standard for supporting the burner.

The combined support and adjuster is 45 shown in Fig. 1 and comprises a casting providing a base 10 and a vertical tubular socket 12, the latter for receiving a supporting post 14 held in any desired vertical or angular relation to its socket by a set screw. The base 10 is generally triangular in plan and is provided with leveling screws and a holding 50 bolt, as shown. An adjuster 16 comprises a

bar having a longitudinal slot 18 and a threaded aperture 20 both being cut through from the upper to the lower face of the adjuster. Conveniently the lower face of the adjuster is rabbeted about the slot providing 55 an interior shoulder 22. The adjuster is attached to the support by screwing it onto the upper end of the post 14 thus forming a horizontal arm on the post.

Many types of domestic ranges have fire 60 boxes so constructed that the base 10 of the support cannot be bolted to the floor with its post 14 central of the width of the fire box. In such installations it is essential that the adjuster of this invention be combined with 65 the support so that, regardless of the lateral position of the base the oil burner can be located centrally laterally or in its correct position with the combustion chambers below the lids in the top of the range. Examples of 70 two such types are illustrated by Figs. 3 and 4 from which the utility of the combined support and adjuster will be understood.

In Fig. 3 the oven wall 24 is inclined to 75 form a chute under the grate when burning coal thus reducing the width of the floor with respect to the width of the fire box above it. Obviously the support cannot be placed far enough inward to permit the post 14 to be threaded directly into the central web 2 of 80 the burner and seat the combustion chambers below the lids. This difficulty is overcome by securing the burner to the adjuster 16 which is turned to project inward over the chute 24 or into the central portion of the fire box.

In Fig. 4 an ash chute 26 extends obliquely 85 into the ash pit, from the outer wall of the range and under this condition the only available position of the support is too far toward the oven to permit seating the burner centrally by a direct connection to the post 14. In this case the post is turned angularly 90 within its socket until the attached adjuster 16 projects outward over the chute or into the central portion of the fire box.

In either illustrated case, or in any similar 95 case where the features of construction of the range prevent a central position, laterally, of the post 14, the burner is secured to the adjuster by a bolt passed through the slot 18, 100

having its head 28 engaging the shoulder 22, and through the perforation in the burner web 2 with a nut 30 on its upper end. Desirably a washer 32 is slipped on the bolt to hold the burner away from its support. Thus the burner may be bolted in such position along the length of the adjuster as will seat it with its combustion chambers beneath the range lids regardless of the lateral position of the base of the support.

10 Some ranges have uneven floors formed by ribs or other obstructions so that it is impossible to bolt the support in its proper longitudinal position relative to the two range lids. In installations where the support is off-center longitudinally the post 14 is loosened and turned angularly within its socket until a portion of the adjuster slot 18 is at the central point whereupon the post is secured 15 and the burner mounted on the adjuster as hereinbefore described. The desired vertical position of the burner is attained by a vertical adjustment of the post 14 within its socket 12.

20 25 The nature and scope of the invention having been indicated, and its preferred embodiment having been specifically described, what is claimed as new is:—

1. An oil burner for use in a range having 30 a fire box of the type in which lateral partitions or the like extend inward and obstruct the lower portion of the space centrally below the range lids, having a substantially vertical support secured in a fixed position within 35 the fire box necessarily laterally off-center with respect to the range lids due to interference by said lateral obstruction with a central securement, said support projecting upward to a point above said obstruction, a 40 combustion chamber carried by said support in the open space above said obstruction, and means intermediate the combustion chamber and the support providing for lateral movement of the combustion chamber relative to 45 said support to center said combustion chamber beneath the range lids regardless of the off-center position of the support necessitated by said lateral obstruction.

2. The invention defined by claim 1 in 50 which said means for centering of the combustion chamber comprises a substantially horizontal arm attached at one end to said support and having a longitudinal slot open at its upper side, and means between said arm and said combustion chamber adjustable within said slot for rigidly mounting said combustion chamber directly above said arm in the required centered position.

3. In an oil burner mounted on a vertical 55 support, for use in a range having a fire box of the type preventing securing the support centrally laterally of the fire box whereby said burner would be laterally off-center with respect to the range lids, provision for centering the burner with respect to the range lids

comprising an adjuster consisting of a slotted, horizontal arm projecting laterally from the support, and means for adjustably securing the burner within said slot to be supported at the upper side of said arm.

4. An oil burner of the type comprising two combustion chambers joined by a central web perforated to receive a supporting post and said combustion chambers to be supported within the fire box of a range centrally beneath the range lids, having means for so centering said combustion chambers beneath the range lids regardless of a required non-centered position of the post for supporting the burner, comprising a vertically slotted arm 80 extending laterally from the post, and means passed through said slot for detachably connecting said central perforated web to the upper side of said arm, said burner being supported above and adjustable along said arm 85 to the desired centered position.

5. An oil burner for use in a range having a fire box of the type in which lateral partitions or the like extend inward and obstruct the lower portion of the space centrally below the range lids, having a substantially vertical support secured in a fixed position within the fire box necessarily laterally off-center with respect to the range lids due to interference by said lateral obstruction with a central securement, said support projecting upward to a point above said obstruction, a combustion chamber carried by said support in the open space above said obstruction, a slotted arm extending laterally intermediate the combustion chamber and the support for connecting said combustion chamber to the support, said slot providing for a variable laterally off-set relation of the combustion chamber relative to said support, and means 90 for securing said combustion chamber in the required off-set relation to the support for centering it beneath the range lids regardless of the off-center position of the support necessitated by said lateral obstruction.
